F. REYNOLDS & G. ZAHN.

Harness Buttons

No. 7,760.

Patented Sept. 15, 1874.

WITNESSED

INVENTOR

UNITED STATES PATENT OFFICE.

FREDRICK REYNOLD AND GEORGE ZAHN, OF NEWARK, NEW JERSEY.

DESIGN FOR HARNESS-ROSETTES.

Specification forming part of Design No. 7,760, dated September 15, 1874; application filed June 1, 1874.
 [Term of Patent 7 years.]

To all whom it may concern:

Be it known that we, F. REYNOLD and G. ZAHN, both of the city of Newark, in the county of Essex and State of New Jersey, have invented certain new and useful Improvements in Design for Rosette for Harness; and we do hereby declare that the following is a full, clear, and exact description thereof, which will enable others skilled in the art to which it pertains to make and use the same, reference being had to the accompanying drawings, and to the letters of reference marked thereon, which form a part of this specification.

The nature of our invention relates to an improved design for rosettes; and it consists in the shape and configuration, as will be more fully described hereafter.

The accompanying drawings represent our invention.

a represents the base of the rosette, which base is formed of two rounding surfaces, *c d*, the upper surface, *d*, being much wider than the one *c*. The part *d* is rounding on top. Upon this is placed the knob *m*, which is of a curved, rounding form, and has a tapering point formed upon its top.

Having thus described our invention, we claim—

A design for rosette, substantially as shown and described.

In testimony that we claim the foregoing as our own invention we affix hereto our signatures in presence of two witnesses.

F. REYNOLD.
 GEORGE ZAHN.
